UNITED STATES PATENT OFFICE.

WILLIAM W. DAVIS, OF CHICAGO, ILLINOIS.

DESIGN FOR A SHOW-CASE.

SPECIFICATION forming part of Design No. 24,599, dated August 20, 1895.

Application filed June 17, 1895. Serial No. 553,136. Term of patent 3½ years.

To all whom it may concern:

Be it known that I, WILLIAM W. DAVIS, a citizen of the United States, residing at Chicago, in the county of Cook and State of Illinois, have invented and produced a new and original Design for Show-Cases, of which the following is a specification, reference being had to the accompanying drawings, in which—

Figure 1 is a side view of my show-case, in perspective, showing the general shape and configuration of the sides and rear end thereof. Fig. 2 is a perspective of my invention, showing the shape and configuration of the front and also the side of my design.

Similar letters refer to like parts in both views of the drawings.

In the drawings, A represents the base or bottom portion of my design.

B represents the upright post or portions of the front corners of the design, said posts having on them a molded portion B'.

C is the back post, and is made of the form and shape as illustrated.

D is the end portion of the back compartment of the design, and has surrounding its upper and back portion the molding or beadings D.

E is the top or cover of the show-case, and projects slightly over the rectangular portion of the case. This top has around its outer portion the beveled part E, as illustrated in the drawings. In the middle of this top is the square cover I, placed centrally.

F represents the sides of the main rectangular portion of the design, which, as illus-

trated, are doubled—that is, there are two thicknesses with a small space between them, which is clearly illustrated in the drawings.

G represents the back or rear panel.

H is the lower or band portion placed below 40 the back panel G.

K is the top portion of the rear or back rectangular part of my design.

J is the back portion of said smaller part.

M represents an opening from the main 45 compartment or rectangular portion into the smaller compartment or rectangular portion, which opening is of the form or shape illustrated in the drawings.

The leading feature of my design is a large 50 rectangular portion or form, with molded corner-posts and panel-sides, a projecting top and bottom portion, the edges of which are beveled and molded respectively, and in connection with said larger rectangular portion or form a smaller rectangular portion, which also has a projecting top and bottom portion, as illustrated in the drawings, said forms being connected on the inner side by the opening M, of the shape and form represented.

Having thus described my invention, what I desire to claim and secure by Letters Patent is—

The design for a show case, substantially 65 as shown and described.

WILLIAM W. DAVIS.
